DISPENSING MACHINE

Fred T. Seegar and William Panitch, Chicago, Ill.

Application February 14, 1944, Serial No. 522,242

3 Claims. (Cl. 312—84)

This invention relates to a machine, or device, for individually dispensing cylindrical objects, such as sanitary soda or drinking straws for fountain or home use in sipping or drinking various beverages from bottles or glasses.

An object of the invention is to provide a simple and economical device for holding a supply of drinking straws or the like, protected from exposure to dirt and dust, and for dispensing the same singly in a clean and sanitary condition, as desired for use by a person, thus obviating the necessity or custom of holding a supply of straws in a carton exposed to unsanitary conditions, dirt and dust, through an opening sufficiently large to permit the entrance of the fingers in removing the straws for use and which usually results in fingering or fumbling over the same with resultant contamination or uncleanliness so undesirable in connection with such practice.

A further object of the invention is to provide a dispensing device which includes a container or hopper for holding a supply of straws and means at the bottom thereof for guiding the straws into grooved seats longitudinally in the periphery of a dispensing roller adapted to be turned by a person desiring a straw so as to singly receive and discharge the same onto an inclined tray or plate down which the discharged straw rolls into a position to permit convenient grasping thereof in the center, and removal without touching the ends of the straw which dip into the beverage, or enter the mouth of the drinker.

Another object of the invention is to provide a dispensing or discharge means which will prevent the straws from feeding more than one at a time, or becoming jammed or clogged with resultant squeezing or crushing, so as to render them unfit for use.

Further objects and advantages will appear, and be brought out more fully in the following specification, reference being had to the accompanying drawings, in which:

Fig. 1 is a front elevation of a dispensing machine, or device, constructed in accordance with the invention.

Fig. 2 is an end elevation thereof.

Fig. 3 is an enlarged vertical longitudinal sectional view, taken on the line 3—3 of Fig. 2.

Fig. 4 is an enlarged horizontal longitudinal sectional view, taken on the line 4—4 of Fig. 1.

Fig. 5 is a vertical transverse sectional view, taken on the line 5—5 of Fig. 3, showing the dispensing roller in position to receive a straw, and

Fig. 6 is a similar view taken on the line 6—6 of Fig. 3, but showing the dispensing roller in

position after receiving a straw, and indicating the discharge positions of the dispensing grooves or seats thereof.

Referring more particularly to the drawings in detail, the dispensing machine or device is shown as comprising a casing 10, which may be of sheet material, such as metal or plastic, of oblong rectangular shape, forming an elongated and relatively deep container or hopper for holding a supply of cylindrical objects, such as drinking straws 11. This casing has a front wall 12, end walls 13 and a rear or back wall 14, the sheet forming which may be joined at one corner by overlapping the ends and soldering, or otherwise 15 fastening the same together, as indicated at 15.

The top of the casing is open and may be closed by a flanged cover 16. Also, the top or other exposed edges of the sheet material may be folded over, as indicated at 17, to avoid sharp edges.

20 The front of the casing may have an opening 18 with a grooved retainer 19 at the top, and a groove 20 at the bottom for receiving and holding a transparent window 21 through which the supply of straws, or other similar objects, may be 25 observed.

The bottom of the hopper is open and the front wall terminates at a point spaced from the bottom where it is directed or bent inwardly at an obtuse angle relative to the upper portion to form 30 a deflector 22. The end walls 13 are cut out intermediately, as indicated at 23, to form recesses at the bottom and provide corner legs 24 for supporting the casing upon a counter, or other horizontal supporting surface.

35 The back wall 14 may extend downwardly the same extent as the legs 24 to prevent access beneath the container or hopper at the rear. Arranged horizontally within the front and back walls 12 and 14 are angular plates 25, having 40 vertical portions bolted, or otherwise secured against the inner faces of said walls, as indicated at 26. Where bolts are used as supporting and retaining means, the front and back, or rear walls are provided with apertures 27 to receive the bolts.

45 The inner portions 28 of the plates are disposed in acute-angled relation to the vertical portions 25 and incline inwardly in opposite directions toward each other to form a container or hopper within the casing for accommodating a 50 relatively large supply of straws 11, or the like. The lower edges of the inclined portions 28 are spaced apart to form a longitudinal opening therebetween, extending almost to the end walls 13.

55 Rotatably mounted in the end walls 13 in and

beneath the opening between said edges, is a rotatably supported circular feeding or dispensing member or roller 29. This roller 29 is somewhat the shape of a spool, having a reduced central cylindrical portion 30 and longitudinally spaced enlarged cylindrical portions 31 of the same size, outwardly thereof, with their peripheries parallel to the axis of the roller 29.

The outer ends of the portions 31 are normal to the axis, and the inner ends of portions 31 are beveled or tapered inwardly at 33 to joint the smaller intermediate portion 30. The enlarged portions 31 are each provided with a pair of diametrically opposite longitudinal seats or grooves 32 in the peripheries thereof parallel to the axis of the roller 29 and extending into the beveled portions 33 at the inner ends of the enlarged portions 31. The extreme ends of the feed roller 29 may have further reduced cylindrical or other portions 34 adjacent the end walls 13 to receive trunnions or shafts 35 at the axial center of the roller 29 for rotatably supporting the latter in bearings 36 supported in the end walls 13.

For this purpose, the end walls may have openings 37, and each of the bearings comprises an inner flanged sleeve 38, the flange of which is disposed against the inner face of the end wall, and the axial portion of which is disposed through an opening and externally threaded to take a nut 39. The ends of the reduced portions 34 are provided with metallic bearing plates 40 inasmuch as the roller 29 may be of wood, although it may be of other material, such as plastic, rubber, or otherwise. The trunnions or shafts may be mounted in and fixed to the ends of the roller, or may extend entirely through the same and have mounted on their outer ends, knobs or handles 41, threaded, or otherwise secured in position so as to fix them to the shaft and roller whereby the roller may be easily turned by hand from either end and in either direction.

The lower edges of the inclined plates 28 are recessed to substantially conform to the peripheral contour of the roller, having recesses 28a at the ends, and a central projection 28b extending in to the recess formed by the reduced portion 30 and the beveled portions 33, in close proximity to the peripheral surface of the roller. In this way, the periphery of the roller 29, together with a straw held in the longitudinally aligned grooves or seats 32, will clear the edges of the portions 28 and the straws will be retained parallel to the axis and prevented from being deflected at an angle or becoming jammed or clogged between the roller and the bottom of the hopper formed by said plates. This insures proper feeding of the straws upon rotation of the roller in either direction.

Disposed beneath the hopper and roller is a forwardly inclined tray or plate 42, which may be held in position by means of a lug 43 secured at its back edge 44, so as to extend through horizontal slots 45 in the back or rear wall 14. This lug is bent downwardly against the back wall to removably secure the tray 42 in position and to permit its removal so that the roller 29 may be entered at the bottom of the casing in assembling the device or for repair and replacement purposes, unless inserted at the top before the angular plates 25 are mounted in position.

The plate forming the tray 42 is supported in a forwardly inclined position by means of lugs 46 directed inwardly at the bottom edges of the end walls 13 at the cutouts or recesses 23, and extends forwardly of the front of the casing where it is turned upwardly, as indicated at 47, to form

retaining means for the straws, which are discharged upon the tray and roll forwardly thereof.

The front edge of the tray at the center is provided with a semi-circular recess or cutout 48 to permit entrance of the fingers in grasping and removing the straws at the center or intermediate of the lengths thereof, and removal without touching the ends of the straws, which are, thus, maintained in a more sanitary condition where they dip into the beverage or enter the mouth of the drinker.

In the use and operation of the device, a supply of straws is dumped into the hopper or container so as to be supported upon the inclined guide plates 28 and the exposed top portion of the roller, which extends slightly upwardly in the space between said plates. When a straw is desired, one, or both of the knobs 41 is grasped by the person desiring the straw, and by turning the same, the roller will be turned so as to present one of the grooved seats 32 in position to receive a straw 11, which will drop into the seat by gravity in the manner shown in Fig. 5 of the drawings, at any point between the edges of the plates 28 at the opening or slot provided therebetween.

As the roller is turned further, in the manner shown in Fig. 6, the straw in the seat will pass beneath the lower edge of a plate 28 so that the roller and the straw will both clear said edge, said plate preventing the other straws from being jammed or clogged, and thus, crushed or mutilated, which would render them unfit for use. In this manner, the straws are delivered unimpaired, and when the groove or seat passes to a point below the axis of the roller, as also indicated in Fig. 6 of the drawings, the straw will drop out by gravity onto the tray 42 and roll down toward the front against the retaining portion 47, there to be easily grasped at the recess or notch 48 and removed, as heretofore explained.

Thus, it will be seen that the straws will be picked up by one of the seats, as the roller is turned, and irrespective of the direction in which the roller is turned, will be carried around with the roller and downwardly to be discharged upon the tray in either of the positions indicated in the solid or dotted lines at the lower portion of the roller 29 in Fig. 6 of the drawings.

The deflector 22 will serve to deflect the straws rearwardly when they are discharged from the roller at the front when turned forwardly, and will prevent a person from passing their fingers upwardly to be squeezed between the front wall and the roller.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. In a dispensing device of the class described, a casing having oppositely inclined walls having their inner edges spaced to form an opening therebetween and a hopper thereabove, a feeding roller horizontally supported for rotation beneath the opening, said roller having a central reduced portion, the edges of the walls being formed with central tongues and end recesses to conform to the periphery of the roller, said roller having a

longitudinal groove in its periphery in the direction of the axis of the roller, and an inclined tray supported below the roller and having a finger recess therein.

2. In a dispensing device of the class described, a casing open at the top and bottom, a cover for the casing, oppositely inwardly inclined walls in the casing having their inner edges spaced to form a central longitudinal opening, a rotatable member journaled in the casing at the ends of the opening and having a central reduced portion and enlarged end portions, longitudinal grooves in said end portions, the edges of said walls substantially conforming to the peripheral contour of the rotatable member and in close proximity thereto, said casing adapted to receive cylindrical objects, such as drinking straws, above said walls to be fed by gravity into the grooves for discharge below the axis of the rotatable member upon turning the latter, means at the ends of the rotatable member for turning the same, and a forwardly inclined tray removably supported in the casing beneath the rotatable member and having a central recess in its lower edge and stops on either side thereof, one side of the casing terminating in spaced relation to the tray.

3. In a dispensing device of the class described, a casing open at the top and bottom, a cover for the casing, oppositely inwardly inclined walls in the casing having their inner edges spaced to

form a central longitudinal opening, a rotatable member journaled in the casing at the ends of the opening and having a central reduced portion and enlarged end portions, longitudinal grooves in said end portions, the edges of said walls substantially conforming to the peripheral contour of the rotatable member and in close proximity thereto, said casing adapted to receive cylindrical objects, such as drinking straws, above said walls to be fed by gravity into the grooves for discharge below the axis of the rotatable member upon turning the latter, means at the ends of the rotatable member for turning the same, and a forwardly inclined tray removably supported in the casing beneath the rotatable member and having a central recess in its lower edge and stops on either side thereof, one side of the casing terminating in spaced relation to the tray.
